UNITED STATES PATENT OFFICE.

BOYDE H. DYE, OF TIPTON, CALIFORNIA.

CORING DEVICE.

Application filed December 9, 1926. Serial No. 153,636.

This invention relates to coring devices and more particularly to a device for relieving pressure within the core barrel proper.

It is well known to those familiar with the art in rotary well drilling apparatus the drill is operated with a water circulation under considerable pressure. The bottom of the well is accordingly filled with muddy water and when the ordinary drill is withdrawn for substitution by a core drill, this mud has a chance to settle, with the result that there is a considerable layer thereof at the bottom of the well. As the core drill is lowered into the well, this mud enters the lower end of the core barrel and if a complete core, the full length of the core barrel, is to be taken, it is necessary that this mud be permitted to escape therefrom. To this end, the upper ends of the core barrel have been provided with outlet openings for mud and water and with check valves controlling such openings, but these devices are all unsatisfactory in that either the core is subjected to the water pressure or the check valve is held against its seat by the water pressure, so that the resistance causes the core to pack and prevents a full core being taken. Accordingly, an important object of this invention is to provide an outlet for the mud and water, which enter the core barrel, as it is lowered into the well, which will not be subjected to the water pressure.

A further object of the invention is to provide a device of this character such that the current produced by the circulation water is not only prevented from exerting its pressure against a check valve controlling the outlet, but is likewise caused to exert a suction upon this outlet, with the result that all pressure on the valve is relieved and the mud and water may readily leave the core barrel.

These and other objects I attain by the construction shown in the accompanying drawings, wherein for the purpose of illustration is shown a preferred embodiment of my invention and wherein:

Figure 1 is a vertical sectional view through the upper end of a core barrel provided with a control mechanism constructed in accordance with my invention;

Figure 2 is a section on the line 2-2 of Figure 1.

Referring now more particularly to the drawings, the numeral 10 generally designates the drill pipe of well drilling apparatus and 11 a core barrel arranged interiorly

thereof to receive a core formed by the drill upon the lower end of the drill pipe (not shown). In accordance with my invention, I provide a hollow member 12, the upper end 13 of which is closed and the lower end of which has a central aperture 14 adapted for connection with the upper end of the core barrel. Associated with this central aperture is a check 15 and seat 16 therefor which act to prevent circulation water from entering the upper end of the barrel.

Communicating with the hollow body adjacent the upper end thereof and diverging downwardly from this hollow body are a pair of outlets 17, the lower ends of which preferably project slightly below the lower surface of the hollow body, as indicated. Associated with this hollow body is an outer sleeve 18 having at its lower end downwardly directed outlets 19. The sleeve 18 has approximately the same outside diameter as the inside diameter of the drill pipe, so that circulation water forced downwardly through the drill pipe will enter through the upper end thereof and leave through the outlets 19. The outlets 17 of the hollow body align with and preferably project into the outlets of the sleeve, with the result that this circulation water, during its passage through the outlets of the sleeve, exerts suction upon the lower ends of the outlet 17 and pressure upon the check valve 15 is relieved so that it may readily leave its seat and permit mud and water contained in the core barrel 11 to pass through the opening of the seat 16.

To assist in directing the water passing through the sleeve 18 downwardly through the outlets 19 of the sleeve, the sleeve at its lower end is provided with a bottom 20 through which the outlets open and the exterior face of the hollow body 12 at opposite sides thereof is provided with pairs of downwardly diverging ribs 21, the outer edges of which come into close proximity to the walls of the sleeve 18 and the lower ends of which extend into close proximity to the upper face of the bottom wall 20 of the sleeve.

In the preferred construction, the check valve seat 16 is carried by the upper end of a nipple 22, which serves with a swedge 23, as a means for connecting the hollow body to the upper end of the core barrel and this nipple is threaded through a central aperture 24 formed in the bottom wall 20

of the sleeve. The top of the hollow body is preferably provided with a removable plug 25 permitting access to the check 15. It will be obvious that this construction is, however, capable of a certain range of change and modification without in any manner departing from the spirit of the invention and I accordingly do not limit myself to such specific structure except as hereinafter claimed.

I claim:—

1. In combination with a core barrel of rotary well drilling apparatus, a hollow body having a closed upper end, said hollow body being in communication with and supported from the upper end of the core barrel, a check valve for controlling communication between the hollow body and the core barrel, downwardly directed outlets for the hollow body communicating with the hollow body above the seat for the check valve and a sleeve surrounding the hollow body having an open top and downwardly directed outlets at its lower end, the outlets of the hollow body aligning with the outlets of the sleeve.

2. In combination with a core barrel of rotary well drilling apparatus, a hollow body having a closed upper end, said hollow body being in communication with and supported from the upper end of the core

barrel, a check valve for controlling communication between the hollow body and the core barrel, downwardly directed outlets for the hollow body communicating with the hollow body above the seat for the check valve and a sleeve surrounding the hollow body having an open top and downwardly directed outlets at its lower end, the outlets of the hollow body aligning with the outlets of the sleeve and extending thereinto.

3. In combination with a core barrel of rotary well drilling apparatus, a hollow body having a closed upper end, said hollow body being in communication with and supported from the upper end of the core barrel, a check valve for controlling communication between the hollow body and the core barrel, downwardly directed outlets for the hollow body communicating with the hollow body above the seat for the check valve, a sleeve surrounding the hollow body having an open top and downwardly directed outlets at its lower end, the outlets of the hollow body aligning with the outlets of the sleeve and means associated with the hollow body and sleeve for directing fluid passing downwardly through the sleeve to said outlet.

In testimony whereof I hereunto affix my signature.

BOYDE H. DYE.
